UNITED STATES PATENT OFFICE.

ROYAL R. MILLER, OF CHICAGO, ILLINOIS, ASSIGNOR TO ADOLPH KARPEN, OF CHICAGO, ILLINOIS.

DAVENPORT OR DIVAN.

1,175,974.

Specification of Letters Patent. Patented Mar. 21, 1916.

Application filed July 11, 1912. Serial No. 708,793.

To all whom it may concern:

Be it known that I, ROYAL R. MILLER, a citizen of the United States, and a resident of the city of Chicago, in the county of Cook and State of Illinois, have invented certain new and useful Improvements in Davenports or Divans; and I do hereby declare that the following is a full, clear, and exact description of the same, reference being had to the accompanying drawings, and to the numbers of reference marked thereon, which form a part of this specification.

The object of this invention is to afford a relatively short divan adapted to be extended laterally in a plurality of folds to afford a bed or davenport.

It is also an object of the invention to afford a construction adapted to fold in very small compass, and comprising a plurality of articulated bed sections adapted to be rigidly supported at or near the articulations thereof when extended, to afford a rigid mattress frame, but the sections of which, when folded inwardly, successively interlock to hold the folded sections in folded position.

It is also an object of the invention to afford a construction in which the divan seat is supported in inverted position upon the mattress frame when extended, and is articulated at its forward edge directly with the divan frame to swing thereon to open and closed position.

It is also an object of the invention to afford a construction wherein the second mattress frame section corresponding approximately in position with the center of gravity of an occupant of the davenport, is positively supported when extended, upon the mattress frame by means of a connection with the seat, the line of support falling substantially in alinement with the front part of the davenport frame.

The invention has other important objects, as will hereinafter more fully appear, and (in a preferred form) is illustrated in the drawings, and hereinafter more fully described.

In the drawings: Figure 1 is a top plan view of a device embodying my invention, showing the back of the davenport removed. Fig. 2 is an end elevation thereof, with the end of the davenport removed, and the device closed. Fig. 3 is a similar view, with the mattress frame half extended. Fig. 4

is a view similar to Fig. 3, and showing the device fully opened. Figs. 5 and 6 (the latter fragmentary) are sections taken on lines 5—5, and 6—6 of Fig. 4, the former showing the legs extended to supporting position, the latter showing the same folded as when the davenport is closed. Fig. 7 is an enlarged, fragmentary detail section with parts omitted, taken on line 7—7 of Fig. 4. Fig. 8 is an enlarged, fragmentary section on line 8—8 of Fig. 4. Fig. 9 is an enlarged, fragmentary detail on line 9—9 of Fig. 3. Fig. 10 is a fragmentary detail section on line 10—10 of Fig. 2 illustrating a detail of the hook. Fig. 11 is an enlarged end elevation of the fall-board or front closing board.

As shown in the drawings: 1, indicates the end frame members of the divan or davenport frame, which may be constructed in any suitable manner; 2, the back or longitudinal end member, which connects said frame members, and in the drawings is shown as extending above the seat at normal position, though, of course, not necessarily.

3, indicates the upholstered (or other suitable) seat, adapted when in normal position to afford the seat for said davenport, and comprising a rectangular frame of any suitable construction and upholstered in any suitable manner, if desired, provided with a front downwardly projected rigid extension or front board 4, provided at its lower end near each edge with a grooved gudgeon 5, which is journaled in a bracket 6, rigidly secured on the end members 1, at the front thereof, as shown in Figs. 3 and 9. Secured at the inner side of said end frame members, are brackets 7, each carrying a gudgeon 8, projecting longitudinally of the frame and a fall-board 9, provided on its inner side near the lower edge with bearing members 10, which respectively engage said gudgeons 8, and are swingingly supported on said gudgeon, as shown, to fill the space between the extension or front board 2, of the seat, and the bottom of the frame to afford a finish when the seat is closed inwardly to normal position, as shown in Fig. 2.

Rigidly secured on each end of the seat frame 3, near the front edge thereof, are downwardly extending standards 11, which, when the seat frame is inverted outwardly,

- as shown in Fig. 4, are directed upwardly and rearwardly with the extremities thereof approximately above the gudgeons 5, on which the seat frame is pivotally supported.
- 5 The mattress frame, when extended, is partly supported on said standards 11, and comprises, as shown, five articulated sections comprising alternately arranged long and short sections 13, 14, 15, 16 and 17 respectively, of which the sections 14 and 16 are the short sections. Said sections are articulated together to adapt said frame to fold inwardly in two folds from the outer end thereof, and into the davenport frame 10 in position shown in Fig. 2. The sections 13 and 17 each comprise the end members constructed of angle bar, and a side member 18, connecting the same at their outer or free ends and affording a strong rectangular frame. The short sections 14 and 16, articulate therewith by means of suitable pintles or bolts extending through the flanges of said angle bars, and the webs and flanges thereof are so arranged as to interlock to 25 limit the outward opening of the same to a horizontal plane. The intermediate long sections 15, articulate in a similar manner with the adjacent ends of the short sections 14 and 16.
- 30 Rigidly secured on the under side of the web of the short angle bar section 14, is a bracket 19, and pivotally engaged therein at its ends in said brackets, and connecting said short frame sections 14, is a bar 20, which 35 may be tubular for lightness. Said bar, intermediate its ends, is bent downwardly, as shown, substantially to the under side of the seat frame, and lies behind the front board 4, as shown in dotted lines in Figs. 3 and 4, 40 and in full lines in Fig. 7, and stops 21, are secured on the under side of the seat frame engaging said bar between the same and said front board 4. Pintles are provided on the outer ends of said bar, on which the extremities of the standards or brackets 11, are 45 engaged, thereby engaging the short mattress section 14, with the seat frame, and utilizing the seat thereby as a lever, fulcrumed on the gudgeons 5, to adjust the 50 mattress frame outwardly and inwardly, and to elevate or depress the same, dependent upon the direction or movement of the seat frame.
- A relatively short leg 22, is pivotally engaged on each end of the mattress frame section 13, and a link 23, pivotally engaged to the short mattress frame sections 14, beyond the hinged pintle, is engaged at its other end on said leg below the fulcrum pivot 24, 60 therefor, so that when the short section 14, is extended in the plane of the section 13, said leg is swung downwardly thereby. A guide rail 25, is secured on each end frame member 1, of the davenport, which extends 65 to an inclined guide member 26, also secured thereon, and inclining upwardly and forwardly, and the upper end of which is at a height and position to receive and support said leg 22, when the mattress frame is extended, as shown in Figs. 3 and 4, and a stop 27, is provided on said end mattress frame member 1, slightly beyond the end of said inclined guide member and support 26, to insure the engagement of the end of said leg on its said support. Strong pulling 70 springs 28, are engaged on the rear or inner end of said mattress frame section at each corner thereof, and also on the end frame members, and act to exert tension on the mattress frame when extended, and also 75 when folded or closed, and assist in balancing the weight in opening the davenport, and when fully opened, as shown in Fig. 4, exert inward tension on the mattress frame.
- Locking cam plates 29, are secured, one on 80 each end at the under side and rear edge of the seat frame, and each is provided with a cam slot 30, in which engages a gudgeon 31, secured to the second long mattress frame section 15, not far from the outer end thereof. Said cam slot is of such shape that when the mattress frame section is folded and closed, as shown in Fig. 2, the mattress frame section 15, lies flat against the under side of the seat frame, and is guided and supported in such position on the seat frame by means of the gudgeon 31, which rides upwardly in said slot owing to the relative movement of the sections 15 and 14. When the mattress frame is extended, however, the travel or movement of the mattress frame section 15, with reference to the seat frame, is equal to the length of said slot 30, and the gudgeon 31, is at the opposite extremity thereof supporting the seat frame thereon, 90 as shown in Figs. 3 and 4.
- A bent bar (tubular or otherwise) 32, is 95 engaged to the short mattress frame sections 16, and serves to space said members a uniform distance apart and to connect the same. Secured on the under side of each of the end members of the mattress frame sections 15, is a bracket 33, which extends beyond the outer extremity, and affords a 100 downwardly extending transverse web directed transversely the mattress frame and pivotally engaged thereon by means of a pintle 34, extending therethrough not far from its upper extremity, is a leg 35, adapted 105 to swing downwardly to supporting position, as shown in Figs. 3, 4, and 5, when the mattress frame is extended, and to swing upwardly along the back of the seat frame, as shown in Fig. 6, when the mattress frame is folded inwardly of the davenport frame. 110 This is accomplished by the relative movement of the mattress frame and seat frame, and, for this purpose, a rod or link 36, is pivotally engaged at one end on the seat frame intermediate the ends of the seat 115 120 125 130

frame, and the other extremity of said bar is pivotally engaged at the extremity of the leg 35, a pintle 37, affording the connection therebetween and acting to swing said leg 5 in either direction by the relative movement of opening or closing the davenport.

Pivotally engaged near its extremity on the extremity of the mattress frame section 17, is a leg 38, which is pivotally connected 10 at its upper end with the end members of the mattress frame section 16, by means of a rod or link 39, so that the relative movement of said mattress frame sections 16 and 17, act to swing said leg to open position, as 15 shown in Fig. 4, or closed position, as indicated in Figs. 2 and 3. As shown, a hook or detent 40, is provided on the outer side of said leg intermediate its ends, and projects inwardly to engage around the end of the 20 mattress frame section 17, to limit the inward swing of said leg, as shown in Figs. 3 and 4. An outwardly projecting locking stud or pin 41, is provided intermediate the 25 ends of the frame bars of the mattress frame section 14, and behind which the otherwise free end of the outer mattress frame section 17, or leg thereof, engages, as shown in full lines in Fig. 2, and in dotted lines in Fig. 3, when the mattress frame is closed. A lock 30 is also pivotally provided for each end of the seat frame when the same is closed inwardly. For this purpose a plate 42, is pivotally supported at its top on a pintle 43, extending therethrough and into the end of the 35 frame, and is provided below said pintle with a substantially horizontal slot in which engages a stud 44, which provides a limited swing for the lower end of said locking plate. Said plate is so shaped as to afford 40 a downwardly and outwardly inclined forward edge, and is provided near its lower end on the front side with a notch or recess affording a shoulder adapted to receive the web 45, on the bracket 33, before described, 45 secured to the mattress frame section 15, when the mattress frame is folded inwardly. A lever arm 46, (which may be integral with said plate) extends forwardly and upwardly alongside the seat frame at the end thereof, 50 into a position that though concealed by the upholstery at the end of the seat frame, admits of said lever being manually engaged to release the locks.

The operation is as follows: When the 55 device is folded and closed, as shown in Fig. 2, the seat frame closes down upon the folded mattress frame, which is supported in part upon the guide rail 25, and in part upon the standard 11, on the seat frame, and 60 the weight of the rear of said folded sectional mattress, and the bedding inclosed therein, is partly balanced by the upward draft of the springs 28. In this position the standards or brackets 11, engage behind the 65 fall board 9, and hold the same outwardly

substantially flush with the front of the seat frame, and front board thereof, as shown in Fig. 2. When it is desired to open or extend the davenport, the levers 46, are actuated to release the locking plates, 70 and the seat frame is engaged and utilized as a lever in swinging the seat frame and mattress frame upwardly and outwardly from the davenport frame, the draft of the spring 28, assisting for this purpose. Such 75 upward and outward movement is accompanied by the extension of the mattress frame sections 13 and 14, into a common plane against the downward and inward tension or draft of the springs 28, and such 80 relative movement acts to swing the supporting legs 22, downwardly, so that as the mattress frame rises to its normally extended position, the lower ends of said legs engage on the upper edge of the guide 26, 85 against the stop 27.

The full inversion of the seat frame, of course, extends the three mattress frame sections 15, as shown in Fig. 2, such extension also causing the fall board to swing back, 90 owing to the slight pressure thereon by the upholstery of the seat frame. The relative movement of the mattress frame section 15, and seat frame, acts to swing the leg 35, downwardly to supporting position. The 95 extension of the sections 14 and 15, into a common plane also retracts the upper ends of the legs 38, from the locking stud or detent 41, leaving the outer section of the mattress frame free to swing downwardly into 100 supporting position, and at the same time extends the legs 38. In this position, an exceedingly strong and rigid alinement of the mattress frame section is afforded, said mattress frame extending substantially with 105 the same rigidity as though the frame was of a unitary construction. In closing the davenport, the reverse operation, of course, occurs.

The lock effected by the locking plate 45, 110 acts automatically, said webs of the bracket 33, striking the inclined edge of the locking plate and forcing the same rearwardly until the notch is reached, when said plate swings forwardly by gravity, engaging said webs 115 and supporting the seat frame in closed position.

Of course, it is to be understood that any 120 suitable mattress fabric may be used in connection with my invention, and that numerous details of the construction and operation may be varied, and it is to be observed that the seat frame does not function to support any portion of the mattress frame when extended, but is utilized principally as a lever 125 in opening and closing the mattress frame. It is also to be observed that the weight of the folded mattress frame, with the bedding inclosed therein, may be supported upon the 130 guide strips 25, when the device is closed.

I have shown but a preferred form of my invention, although numerous variations in construction and operation may obviously be effected. I therefore do not purpose limiting the patent granted on this application, otherwise than necessitated by the prior art.

I claim as my invention:

1. In a device of the class described, a davenport frame, a seat frame hingedly connected at its ends thereto adapted to be swung outwardly therefrom into inverted position, a sectional mattress frame adapted to fold within said davenport frame comprising inner, outer and intermediate long sections, short sections pivotally connected between said respective long sections, connections between said seat frame and said sectional mattress frame to extend the same when said seat frame is swung outwardly into inverted position, a plurality of legs connected to said mattress frame to support the same when said frame is extended comprising longitudinally swinging legs on the inner long section, transversely swinging legs on the intermediate long section and longitudinally swinging legs on said outer long section, and means operating to actuate said legs automatically when the mattress frame is extended.

2. In a device of the class described, a davenport frame, a seat frame hinged thereto adapted to swing outwardly therefrom into inverted position, a sectional therefrom frame associated with said davenport frame and said seat frame connected to be extended when said seat frame is swung outwardly and to fold inwardly wholly within said davenport frame when said seat frame is swung inwardly, said mattress frame comprising a plurality of hingedly connected sections consisting of inner, outer and intermediate long sections, short sections pivotally connected between said long sections, a plurality of longitudinally swinging legs for supporting said inner and outer long sections, and transversely swinging legs for supporting said intermediate long section of the mattress frame, each of said legs swinging automatically and positively into a supporting position to support the respective long sections when the mattress frame is extended for use.

3. In a device of the class described a sectional mattress frame, a davenport frame, a seat frame fulcrumed therein, to turn outwardly, connections between the seat frame adjacent the fulcrum and one of the sections of the mattress frame, whereby the seat frame acts as a bent lever in adjusting the mattress frame, means slidably supporting the seat at its otherwise free edge on one of the sections of the mattress frame, a swinging leg for supporting the outer portion of the mattress frame, connections for operating said leg actuated by the relative movement of the seat frame and mattress

frame, an outermost mattress frame section, an automatically adjustable leg pivotally supported thereon, and an outwardly projecting locking stud on one of the inner mattress frame sections adapted to receive the end of said leg thereagainst to lock the outer fold.

4. A device of the class described comprising a foldable sectional mattress, a davenport frame, a seat frame pivotally engaged to the davenport frame at and below its front edge, a fall board hingedly supported in the davenport frame below the front board of the seat frame and adapted to be swung backwardly by contact with said front board when the davenport is opened, means movably supporting the seat frame at its rear edge when opened, on the mattress frame, and rigid arms on the seat frame adjacent to the pivot or fulcrum therefor and extending therebeyond and pivotally engaging the mattress frame and adapting the seat frame to act as a lever in opening and in closing the device, said arms or standards extending back of the fall board when the device is closed to press the fall board outwardly.

5. In a device of the class described, a davenport frame, a seat frame pivotally connected thereto to swing outwardly therefrom in inverted position, bracket plates secured on the under side of said seat frame adapted to project upwardly beyond the pivot connection between said seat frame and davenport frame when said seat frame is inverted, a sectional mattress frame connected to said davenport frame and said seat frame and to the brackets on said seat frame, said sectional mattress frame comprising inner, outer and intermediate long sections, short sections pivotally connected between said long sections, certain of said short sections connected to the bracket plates on said seat frame, supporting legs pivotally connected on each of the respective long sections, and actuating means for each one thereof adapted to move the same into a supporting position when the mattress frame is extended.

6. In a device of the class described, a davenport frame, a seat frame hingedly connected thereto adapted to be swung outwardly into inverted position from said davenport frame, a sectional mattress frame connected between said seat frame and davenport frame adapted to be folded within said davenport frame beneath said seat when said seat is in normal position on the davenport frame and to be extended into position for use when said seat is swung outwardly in inverted position from said davenport frame, said mattress frame comprising a plurality of sections pivotally connected one to another, said sections consisting of alternate long and short sections, a leg connected to each one of said long sec-

- tions, a positively operating actuating means for each one of said legs to swing the same into supporting position when said mattress frame is extended, certain of said legs swing-
5 ing longitudinally and others transversely with respect to said mattress frame, and guiding means mounted on the davenport frame for the supporting legs of the inner-
most section of the mattress frame.
- 10 7. In a sofa bed, the combination of a stationary frame, a couch seat which is hinged to said frame and is adapted to be inverted in front thereof, and a folding bed bottom having a frame comprising connect-
15 ed inner, outer and intermediate sections ar-
ranged to fold with said outer section be-
tween said intermediate and inner sections, a plate rigidly secured on the underside of said seat, a gudgeon on the intermediate sec-
20 tion affording a connection to said plate adapted to move relatively thereto to hold said seat suspended below said intermediate section when the seat is inverted, supporting means which connect said inner section to said stationary frame and permit said inner section to rise and fall when the couch seat is swung from and to its normal posi-
25 tion, and supporting means for said outer section.
- 30 8. In a sofa bed, the combination of a stationary frame, a couch seat which is hinged to said frame and is adapted to be inverted in front thereof, and a folding bed bottom having a frame comprising connect-
25 ed inner, outer and intermediate main sec-
tions and a spacing section between said outer and intermediate sections arranged to fold with said outer section between said intermediate and inner sections, a standard rigidly
- secured on the seat, a second spacing section 40 connected therewith, said intermediate sec-
tion being mounted on the underside of said couch seat by pivotal connection with said second spacing section, and supported above the seat when the seat is inverted, movable 45 supporting means connecting said inner sec-
tion with the stationary frame, guiding means therefor mounted on said stationary frame, and supporting means for said outer section. 50
9. In a sofa bed, the combination of a sta-
tionary frame, a couch seat which is hinged to said frame and is adapted to be inverted, a folding bed bottom which has a rectangu-
55 lar frame which is complete in itself inde-
pendently of said couch frame and seat and which is adapted to be folded with the outer end portion thereof between the intermediate and inner end portions thereof, slotted cam plates rigidly secured on said couch seat, gudgeons on the intermediate portion and engaged in said cam slots to secure said intermediate portion on the underside of said couch seat and to support the seat be-
60 low said intermediate section when the seat is inverted, and movable supporting means connecting said inner end portion of the bed bottom with the stationary couch frame and co-operating with said intermediate por-
65 tion of the bed bottom to support said in-
70 nner end portion, substantially as set forth.

In testimony whereof I have hereunto
subscribed my name in the presence of two
subscribing witnesses.

ROYAL R. MILLER.
